UNITED STATES PATENT OFFICE

WALTER W. SIBSON, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA

DRYING FORM

Application filed July 18, 1929. Serial No. 379,100.

This invention relates to forms for drying articles of textile manufacture such as hosiery and the like. More specifically, it has reference to a drying form of the type shown 5 and described in a co-pending application Serial Number 356,414, filed April 19, 1929, by John W. Dennis which is characterized by having an extensible portion whereby the form is adaptable to drying of articles of different 10 sizes. In the form of the application referred to, the extensible portion is held projected by a spring with capacity to recede as the article is drawn over the form, the latter being thus rendered self-adjusting without 15 ability, however, to determine uniformity in the shaping of articles of any one size.

The object of my present invention is to overcome the deficiency to which attention has just been directed with a view toward 20 enhancing the utility of the form. This desideratum I attain, as hereinafter fully explained, through provisions whereby the extensible portion of the form is yieldingly but definitely retained in different positions of 25 adjustment in accordance with the particular nominal size of the articles which are to be dried to the end that uniformity in shaping and finishing of the articles is preassured.

With reference to the drawings, Fig. I is a 30 fragmentary side view of a hosiery drying form conveniently embodying my invention, a portion of the structure being broken out and shown in section to better illustrate certain important details; and,

Fig. II is a fragmentary edge elevation of 35 the form viewed as indicated by the arrows II-II in Fig. I.

The form chosen for the purpose of illustration herein is intended to be used for drying and shaping hosiery, and its body 5 is accordingly made flat and given the proper profile configuration to serve the indicated purpose. The body 5 is constructed with a co-extensive internal hollow 6 through which 40 a suitable heating medium—such as steam or hot water—may be circulated, or into which an electric heating element may be placed in ways apparent to those skilled in this art.

For adaptability to drying stockings with 45 feet of varying sizes, the form is fitted with an

extensible portion, that is to say, a heel piece 7 which is movable outward through an edge slot 8 of the form body 5, said edge slot being set apart and completely isolated from the hollow 6 by a partition 9 of irregular shape. 55 The extensible heel piece 7 is fashioned to the configuration shown from thin sheet metal, and has pivotal connection at its lower end for swinging movement on a rivet 10 that passes crosswise through the body 5. The outward movement of the heel piece 7 is limited through engagement of a tongue 11 at its upper free end with a stop projection at 12 within the edge slot 8. To determine the proper positions of the extensible heel piece 7 for stockings of different nominal sizes, it is 60 fitted with a spring finger 13 which is selectively engageable with rest notches 14 disposed in serial relation along a projection 15 of the partition 9 within the edge slot 8 of the form body 5. The finger 13 is preferably 65 made from comparatively stiff spring wire with a loop at 16, and it is secured to the extensible heel piece 7 at spaced points below the loop by screws 17. The free end of the 70 finger 13 is rounded as at 18 for capacity to ride readily over the barriers between the rest notches 14 upon exertion of sufficient energy to overcome the spring resistance incident to making positional adjustments of the 75 extensible heel piece 7.

I have thus provided a very simple and inexpensive arrangement whereby the extensible heel piece 7 is yieldingly maintained in different positions of adjustment, so that stockings of any nominal size within the range of such adjustment are all uniformly shaped 80 and finished on the form.

My invention can obviously be incorporated, with advantages equal in all respects 85 to those hereinbefore pointed out, in other portions of a stocking form, as well as in forms for shaping articles other than hosiery. Certain of the appended claims are therefore 90 to be construed with this broad aspect of my invention in mind.

Having thus described my invention, I claim:—

1. A form for drying articles such as hosiery and the like having a pivoted portion 100

- whereby the form may be adapted to drying articles of various sizes; serial notches in the form; and means co-active with said notches for yieldingly but definitely holding the pivoted portion aforesaid in different positions to pressure uniform shaping and finishing of the articles within the range limits of such adjustment.
2. A form for drying hosiery and the like having a pivoted portion whereby the form can be adapted to drying articles of various nominal sizes; means affording notches arranged in serial relation; and means for yieldingly but definitely holding the pivoted portion in selective positions of adjustment including a spring finger shiftable from one to another of the rest notches aforesaid.
3. A form for drying hosiery and the like having a pivoted portion whereby the form can be adapted to dry articles of various sizes; means affording serial rest notches in the form body; and a spring finger on the pivoted portion shiftable from one to another of said notches to yieldingly but definitely hold said pivoted portion in selective positions of adjustment.
4. A form for drying articles such as hosiery and the like having a pivoted portion whereby the form can be adapted to articles of various sizes, means affording serial rest notches in the form body, and a spring finger shiftable from one to another of the rest notches to hold said pivoted portion in yieldingly but definitely selective positions of adjustment, the end of the finger being rounded to facilitates its riding over the barriers between the rest notches upon exertion of sufficient force to overcome the spring resistance incident to making adjustments of said pivoted portion.
5. A form for drying articles such as hosiery having a pivoted heel portion whereby the form can be adapted to drying articles of various foot sizes; and means for yieldingly but definitely holding said heel portion in different positions of adjustment.
6. A form for drying articles such as hosiery embodying a profile body; a pivoted heel portion movable outward through an edge slot in the body whereby the form can be adapted to drying articles of various foot sizes; and means within the edge slot aforesaid for yieldingly but definitely holding said heel portion in selective positions of adjustment.
7. A form for drying articles such as hosiery comprising a form made hollow for the purposes of heating from within; a pivoted heel portion movable outward through an edge slot isolated from the hollow of the body whereby the form can be adapted to drying articles of various foot sizes; and means within the edge slot for yieldingly but definitely holding the heel portion aforesaid in different positions of adjustment.

8. A form for drying articles such as hosiery comprising a profile body; a pivoted heel portion movable outward through an edge slot in the body whereby the form can be adapted to drying articles of various foot sizes; and a spring finger on the heel portion shiftable from one to another of a number of rest notches arranged in serial relation within the edge slot of the form body to yieldingly but definitely hold said heel portion in selective positions of adjustment.

In testimony whereof, I have hereunto signed my name at Philadelphia, Pennsylvania, this 16th day of July, 1929.

WALTER W. SIBSON.

CERTIFICATE OF CORRECTION.

Patent No. 1,833,877.

Granted November 24, 1931, to

WALTER W. SIBSON.

It is hereby certified that error appears in the printed specification of the above numbered patent requiring correction as follows: Page 2, line 6, claim 1, for the word "pressure" read preassure; and that the said Letters Patent should be read with this correction therein that the same may conform to the record of the case in the Patent Office.

Signed and sealed this 2nd day of February, A. D. 1932.

(Seal)

**M. J. Moore,
Acting Commissioner of Patents.**
